United States Patent Office

Des. 214,578
Patented July 1, 1969

214,578

TUMBLER OR SIMILAR ARTICLE

Marvin G. Yutzey, Moundsville, W. Va., assignor to Morgantown Glassware Guild, Inc., Morgantown, W.
Va.

Filed Dec. 20, 1967, Ser. No. 9,860

Term of patent 14 years

Int. Cl. D7—01

U.S. Cl. D36—8

FIG. 1

FIG. 2

FIG. 3

FIGURE 1 is a side elevational view of a tumbler or similar article illustrating my novel design;

I claim:

The ornamental design for a tumbler or similar article, as shown and described.
